UNITED STATES PATENT OFFICE.

WILLIAM ROTSTED, OF CHICAGO, ILLINOIS.

DESIGN FOR A THERMOMETER.

SPECIFICATION forming part of Design No. 34,025, dated February 5, 1901.

Application filed December 24, 1900. Serial No. 40,985. Term of patent 7 years.

To all whom it may concern:

Be it known that I, WILLIAM ROTSTED, a citizen of the United States, and a resident of Chicago, in the county of Cook and State of Illinois, have invented and produced a new and original Design for Thermometers, of which the following is a specification, reference being had to the accompanying drawing, forming a part thereof.

10 The accompanying drawing shows a perspective view of a thermometer-frame made according to my new design.

The leading or material feature of my design consists in the ear of corn forming the body or frame of the thermometer, two of the husks of the corn tied in the form of a bow at the base of the ear and other husks twisted to form the loop projecting upwardly behind and rising above the middle part of said bow.

20 The ear of corn 1 is shown in the drawing with its natural base at the top of the view. Said ear has on the front a pad 2, formed of a series of layers of corn-husks. The pad is considerably shorter than the ear and mounted so as to show part of the ear above and part below the pad. The graduated thermometer-plate 3 is mounted on the face of the pad 2 and is shorter and narrower than the pad. Two of the corn-husks are tied to form the bow 4 at the base of and toward the front of the ear of corn. The other husks, located behind said bow, are twisted and fastened to form the loop 5.

What I claim as new, and desire to secure by Letters Patent, is—35 The design for a thermometer, substantially as herein shown and described.

Signed by me at Chicago, Illinois, this 2d day of December, 1900.

WILLIAM ROTSTED.
